(57) CLAIM

The ornamental design for a magnetic knife holder, as shown and described.

DESCRIPTION

FIG. 1 is a front and top perspective view of a magnetic knife holder, showing my new design;

FIG. 2 is a front, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate the portions of the magnetic knife holder that form no part of the claimed design.
